United States Patent Office

Des. 220,991
Patented June 22, 1971

220,991

SUN SHADE

Mildred Smith Riley, 2735 NE. 14th St.,
Fort Lauderdale, Fla. 33304

Filed May 21, 1970, Ser. No. 23,084

Term of patent 14 years

Int. Cl. D3—03

U.S. Cl. D88—3

FIG. 1 is a front elevational view of a sun shade showing my new design;

FIG. 2 is a side elevational view;

FIG. 3 is a rear elevational view;

FIG. 4 is a top plan view;

FIG. 5 is a bottom plan view; and

FIG. 6 is a front elevational view with the shade in a changed position.

I claim:

The ornamental design for a sun shade, as shown:
